[57] CLAIM

The ornamental design for a business card scanner, as shown and described.

DESCRIPTION

FIG. 1 is a front view of the inventive design for a business card scanner;

FIG. 2 is a top view of the inventive design of FIG. 1;

FIG. 3 is a bottom view of the inventive design of FIG. 1;

FIG. 4 is a left side view of the inventive design of FIG. 1;

FIG. 5 is a right side view of the inventive design of FIG. 1;

FIG. 6 is a rear view of the inventive design of FIG. 1;

FIG. 7 is a cross-sectional view of the inventive design of FIG. 1 taken along the lines 77 of FIG. 1;

FIG. 8 is a perspective view of the inventive design of FIG. 1 with a cover of the business card scanner closed, on an enlarged scale;

FIG. 9 is a perspective view of the inventive design of FIG. 1 with a cover of the business card scanner open, on an enlarged scale;

FIG. 10 is a front view of the inventive design of FIG. 1 with the cover open;

FIG. 11 is a top view of the inventive design of FIG. 1 with the cover open;

FIG. 12 is a bottom view of the inventive design of FIG. 1 with the cover open;

FIG. 13 is a left side view of the inventive design of FIG. 1 with the cover open;

FIG. 14 is a right side view of the inventive design of FIG. 1 with the cover open; and,

FIG. 15 is a rear view of the inventive design of FIG. 1 with the cover open.
